UNITED STATES PATENT OFFICE

GEORGE F. PAWLING, OF PHILADELPHIA, PENNSYLVANIA, ASSIGNOR, BY MESNE ASSIGNMENTS, TO SARAH BELLEVUE PAWLING, OF GLENNSIDE, PENNSYLVANIA

BUILDING STRUCTURE

Application filed November 24, 1928. Serial No. 150,415.

This invention, generally stated, relates to building structures, and has more especial relation to studding and studding accessories.

The leading object of the present invention is to provide a studding possessed of strength and rigidity and of fire-proofing characteristics which may be manufactured at relatively small cost for erection by unskilled labor.

10 A further object is to provide a studding of the character above stated in which specially designed metal form may be used as a casing or housing to receive a fire-proofing composition.

15 Other and further objects reside in the provision of a certain accessory for attaching a stud with respect to a floor and ceiling and in the provision of another accessory whereby studs may be attached with respect to skeletonized joist.

20 With these and other objects in view, the invention consists of the novel construction hereinafter described and finally claimed.

The nature, characteristic features and 25 scope of the invention will be more fully understood from the following description taken in connection with the accompanying drawings forming part hereof, and in which:

Fig. 1 is a view in perspective of a sheet 30 of specially designed metal form as employed as a casing or housing for the composition used in my studding.

Fig. 2 is a view in perspective of a completed stud.

35 Fig. 3 is a view in perspective of a retainer for the end of a stud embodying the invention.

Fig. 4 is a view in perspective of a retainer for a stud embodying the invention as employed in connection with skeletonized 40 joist.

Fig. 5 is a view, partly in cross-section, illustrating a stud as secured by a retainer to a floor and ceiling.

45 Fig. 6 is a view in side elevation illustrating the manner of attaching my stud to a skeletonized joist; and

Fig. 7 is a fragmentary view taken upon the line 7—7 of Fig. 6.

50 For the purpose of illustrating my in-

vention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

55 Referring to the drawings in detail, and with especial relation to Figs. 1 and 2, the reference numeral 1 designates a sheet of specially designed metal form of a type I prefer

because of good results obtained in practice. Obviously other types of metal form may be employed. The metal form illustrated is provided with spaced ribs or beads 2 and between these ribs on the opposite side of the

50 form are other beads and struck-out portions or loops 3, the latter in practice presenting a staggered effect. I take a sheet of specially designed metal form and arrange the

55 same into a tube 4 of rectangular cross-section, see Fig. 2, the ribs or beads 2 providing definite lines upon which to bend the sheet of metal form into tube configuration.

I next fill the tube, so fashioned, with a suitable plastic material of cementitious characteristics and before the same sets I secure the meeting portions of the tube together by driving nails 5 through the metal forms into the material 6. In the connection it is

60 to be noted that the struck-out portions 3 project into the tube, thus affording a mechanical bond with the plastic material and effecting a continuous reinforcing for the stud and the protection of the plastic material.

65 Taking up now Figs. 3 and 5, a description will be given of the manner of using a stud as formed in accordance with the above complete article of manufacture. In Fig. 5,

70 the reference numeral 7 designates a floor and the reference numeral 8 a ceiling. In order to secure a stud, as described, to a floor and ceiling use is made of sheet-metal member of one-piece, stamped out to form a vertical, hollow body 9 of rectangular cross-section

having extended therefrom wings 10, of which there are four. These wings are apertured, as at 11, so that a retaining device as just described, may be nailed to place, upon a floor or a ceiling to receive the stud of fire-proofing material. With a stud properly positioned with respect to bottom and top members above described the stud is nailed fast to these members as at 12, as clearly illustrated in Fig. 5.

Instead of securing the studs between ceiling and floor as just described, it is sometimes desirable and necessary to secure same with respect to skeletonized joist, particularly in outside wall construction. In such case, use is made of the device shown in Fig. 4. The same comprises a one-piece, sheet metal member bent to the configuration shown in Fig. 4, and comprises a pair of spaced, parallel, vertical pieces 13, connected by a cross-piece 14, which pieces 13 each terminate in a horizontal bar 15 the end of which has a flange 16. This structure is particularly adapted to co-act with skeletonized joist having upper and lower T-shaped bars 17, see Figs. 6 and 7. In practice the parts 13-14 are fitted over the T-bar 17 of a joist and the stud of the invention is then fitted between the flanges 16 so as to abut against the horizontal bars 15 and the flanges 16 and the stud secured together as by nails 18.

Among the advantages of my novel building structure, mention may be made of the following:

35 The stud casing is a specially designed metal form made from sheets of flat steel which are passed thru steel rolls designed to form a bead on one side of the sheet steel and reinforcing beads and loops on the opposite side so that no particular care is required in the bending of the plate into tube configuration with the reinforcing loops on the inside.

40 The stud casing may be filled with a composition of wood shavings, gypsum and cement so that it becomes a solid reinforced stud, the reinforcing loops being incorporated in the poured aggregate and when the aggregate is set and dry, its weight is approximately 50% more than wood and it can be nailed into and handled in construction in the same general manner as wood. It has approximately 50% more strength than an equal size wood section and is fireproof. The stud is always uniform in size, straight and true.

45 The principal use of this stud is to take the place of steel studs which are more costly, not as economical to handle in building construction, and which are not as thoroughly fireproof as this stud.

The setting of all these studs is very simple and the nailing is equal to the nailing in any ordinary wood stud.

50 The fastening of the lath for plastering is done with nails or staples in the same man-

ner as with a wooden stud, and without all the costly wiring that occurs in using steel studs.

Instead of using double studs for door bucks and other openings as is customary, the 70 stud is made with a larger cross section.

Wood studs are never sawed carefully and their dimensions therefore are never uniform. A percentage of even the best grade of studs are found to be out of line and even after they 75 are placed in the building, get out of line and entail an additional cost in the lathing and plastering to make a straight edge plaster finish. Wood studs are bought of uniform length and in making them fit in their 80 proper height, considerable waste occurs thru sawing off the unnecessary length of stud. Wood studs are placed 16" on centers while my studs may be spaced 2' on centers. Where my studs are used in connection with outside 85 walls, any building material that is required for exterior treatment can be used in exactly the same manner as wood studs. Additional thickness in walls for architectural treatment can be obtained by increasing the width of 90 the stud or making a stud with two 2 x 3's trussed together.

What I claim is:

1. In a building construction a stud comprising a sheet of ribbed metal form folded along said ribs to form a tubular member and having struck-out portions inwardly projected, a filler within the tube which filler and struck-out portions are interlocked and form a member of solid cross-section, and means penetrating said metal lath to secure the meeting edges of the metal lath to said filler. 95

2. In a building construction a stud comprising a sheet of ribbed metal form folded along said ribs to form a tubular member of rectangular cross-section and having struck-out portions inwardly projected, a filler within the tube which filler and struck-out portions are interlocked and form a member 100 of solid cross-section, and means penetrating said metal lath to secure the meeting edges of the metal lath to said filler. 105

3. In a building construction a stud comprising a sheet of ribbed metal form folded along said ribs to form a tubular member of rectangular cross-section with its struck-out portions inwardly projected, a filler within the tube which filler and struck-out portions are interlocked and form a member of solid 110 cross-section, and means as nails penetrating said metal lath to secure the meeting edges of the metal form to said filler. 115

4. As a new article of manufacture, a stud composed of a metal shell with an inner fill of nailing material, together with means on the shell projecting into the fill, said means being formed with an outwardly presented face around which the fill is adapted to extend so as to come between said face and the 120 125 130

plane of the shell proper whereby to provide a positive mechanical bond or interlock between the shell and the fill.

5. As a new article of manufacture, a stud composed of a metal shell with an inner fill of nailing material, together with a plurality of inwardly extending projections distributed throughout the surface of the shell, said projections being formed with an outwardly presented face around which the fill is adapted to extend so as to come between said face and the plane of the shell proper whereby to provide a positive mechanical bond or interlock between the shell and the

15 fill for the distribution of the stresses.

6. As a new article of manufacture, a stud composed of a sheet of metal lath bent to form a shell and having a plurality of inwardly projected struck-out portions, together with an inner fill of nailing material, said struck-out portions being formed with an outwardly presented face around which the fill is adapted to extend so as to come between said face and the plane of the shell proper whereby to provide a positive mechanical bond or interlock between the shell and the fill for the distribution of stresses.

7. As a new article of manufacture, a stud composed of a sheet of ribbed metal folded along said ribs to form a shell and having inwardly projected struck-out portions, and an inner fill of nailing material, said struck-out portions being formed with an outwardly presented face around which the fill is adapted to extend so as to come between said face and the plane of the shell proper whereby to provide a positive mechanical bond or interlock between the shell and the fill for the distribution of stresses.

40 GEO. F. PAWLING.
